MACHINE FOR MAKING BUTTONS AND THE LIKE.

1,218,742.

Specification of Letters Patent.

Patented Mar. 13, 1917.

Application filed May 9, 1913. Serial No. 766,530.

To all whom it may concern:

Be it known that I, HUGO BRAND, director, a subject of the Emperor of Austria-Hungary, residing at Deutsch-Beneschau, Ringplatz, in the Empire of Austria-Hungary, have invented certain new and useful Improvements in Machines for Making Buttons and the like, of which the following is a specification.

10 This invention has for its object to provide an improved machine for the manufacture of buttons of metal and the like articles consisting of an upper and a lower part, or of an upper, lower, and middle part, of which each part is cut from sheet metal or the like.

In a machine according to the invention for the manufacture of buttons or the like articles each consisting for example of an upper part and a lower part, the pressing matrices for the lower article parts are mounted in a first slide and the pressing dies for the upper article parts are mounted in a second slide, said slides being movable apart 20 from each other, to come opposite to the corresponding cutting dies and by being pushed toward each other the pressing dies of the one slide are placed directly over the pressing matrices of the other slide; the parts 25 thus placed one above the other may be united directly by means of pressure.

As the lower parts of the buttons are smaller than the upper parts, in order to avoid waste of material, the dies for cutting 30 out the lower parts of the buttons must be spaced or pitched more closely together than the dies for cutting out the upper parts of the buttons and the pressing dies corresponding to the latter dies. Therefore the pressing matrices when they are under the cutting block for the lower part of the buttons must have the same pitch as the cutting dies for the lower button parts in order to be able to take up the lower button parts directly from 40 their cutting dies.

However, after the lower button parts have been so taken up and the slide carrying the matrices with the lower button parts has been shifted to below the slides carrying the 50 pressing dies, the pressing matrices must have the same pitch as the cutting and pressing dies for the upper button parts in order to enable the pressing dies and the upper parts of the buttons hanging on the same,

to be introduced into the pressing matrices 55 above the lower parts of the buttons contained therein, so that the upper button parts can then be united to the lower button parts.

According to the present invention, the 60 further arrangement is therefore made, that the pressing matrices which may be disposed in two or more rows, are made positively movable in the longitudinal direction, as well as in the transverse direction, so that 65 they can be adjusted to the pitch of the cutting dies for the lower button parts and also to the pitch of the pressing dies.

For the manufacture of buttons, each consisting of an upper, middle, and lower part, 70 the arrangement may be such that a cutting block for the middle button part is provided besides the cutting block for the lower button parts. The slide which carries the lower article parts may be movable underneath 75 matrices for the manufacture of the middle article parts, in order to shift these middle article parts upon the lower article parts, whereupon by moving the slide for the lower article parts both the lower and middle article parts may be placed underneath the upper article parts and united together with the latter.

Two forms of the improved machine are illustrated by way of example in the accompanying drawings, in which:—

Figure 1 is a longitudinal section of one embodiment of the machine for manufacture of buttons consisting of an upper and lower part.

Fig. 2 is a vertical cross section through the left part of the machine.

Fig. 3 is a horizontal cross section.

Fig. 4 is a vertical longitudinal section through the central part of the machine with 95 superposed dies for putting together the upper and lower parts of the buttons.

Fig. 5 is a plan view of the slides with the pressing matrices.

Fig. 6 is a section on the line *e-f* of 100 Fig. 5. The pressing matrices shown in this figure are curved, while the matrices shown in Fig. 1 are square.

Fig. 7 is a section of the slide for the pressing dies on the line *i-k* of Fig. 1. 105

Fig. 8 is a section of the slide on the line *l-m* of Fig. 1.

Fig. 9 is a vertical section of another

embodiment of the machine for making buttons consisting of upper, middle and lower parts.

Figs. 10 and 11 show a construction of a device for removing the complete buttons.

Figs. 12 and 13 show the elements of the buttons consisting of two parts, separately.

Fig. 14 shows the same in assembled position.

19 As shown, the machine comprises an apparatus for punching or piercing and for cutting out the lower button parts, an apparatus for cutting out, drawing, and piercing the upper button parts, and an apparatus located between the two latter devices for uniting the upper and lower button parts to each other.

The plate strips (Fig. 2) of sheet metal or the like, for the upper and lower parts, 20 are fed by means of feeding rolls 38 or in any other suitable manner, in the direction of the arrows between the cutting dies and the cutting matrices; preferably preliminarily to their introduction into the machine 25 the strips are dished and if necessary pierced. The plate strip for the lower parts is introduced at 34^a (Fig. 1) and the plate strip for the upper parts at 35^a into the machine.

30 The apparatus for the manufacture of the lower button parts consists essentially of a punching mechanism for the preliminary pressing (see *a* Fig. 2) and for the finishing punching, and if necessary also for 35 piercing the lower button parts (not shown). In front of this punching mechanism is a cutting block 34 with cutting dies 5 (Figs. 1 and 2). The dies 5 coöperate with cutting matrices 5^a and enter the same while cutting out the lower parts of the buttons. 40 After the cutting operation the dies 5 thread the cut out, punched, and if necessary pierced, lower button parts onto the pins 3^a of bolts 3 inserted through the pressing matrices 2. The pressing matrices 2 are deepened square as shown at 2^a Fig. 1 or 45 they are curved as shown in Figs. 6 and 10. The pins 3^a can also be employed for piercing the lower button parts. Preferably the pins 3^a coöperate with holes in the cutting dies 5.

The lower parts of the buttons are cut out while the bolts 3 are moved upwardly 55 in such a manner, that the pins 3^a enter the holes of the dies 5 at the moment of the latter touching the matrices 5^a, whereupon the cut out lower button parts which are shifted upon the pins 3^a of the bolts 3, are lowered 60 upon the pins 3^a of the bolts 3, are lowered into the pressing matrices 2.

In accordance with the usual provision of four holes for sewing on the buttons, four pins 3^a may be provided on the bolts 3, entering four holes in the dies 5.

65 The apparatus for manufacturing the up-

per part of the button consists of a cutting block 35 with cutting dies 8 (Fig. 1), which coöperate with cutting matrices 10 through which are guided drawing dies 9, which convey the cut-out upper part of the button 70 into the matrices 10 and thereby effect the turning over of the edge. Above the cutting block 35 is guided the slide 6 (Figs. 1, 7 and 8) which, in the example shown, is movable toward and above the slide 1, carrying the pressing matrices 2 (Fig. 1). In the slide 6, the pressing dies 7 are mounted on a plate 16. Through the press dies 7 pass the pins 11^a of the piercing dies 11, which, in connection with corresponding holes in 80 the drawing dies 9, pierce the upper parts of the buttons (Figs. 1 and 8) and receive them threaded on to the pins 11^a. In order to prevent the return of the piercing dies 11, when piercing the upper button parts, stops 85 are provided, for instance screws 75, which prevent the plates 18 and 19 in which the piercing dies 11 are inserted and held tight, from going backward (Fig. 7).

For uniting the upper and lower button 90 parts which are cut-out by the cutting dies 5 and 8, and pierced by the piercing dies 3 and 11, the two slides 1, 6 are mounted so as to be movable toward each other, whereby the lower button parts contained in the 95 pressing matrices 2, and the upper button parts, threaded on the pins of the piercing dies 11, are located adjustably above each other (Fig. 4).

As the lower button parts which are 100 stamped close to each other are smaller than the upper button parts, provision is made in the machine for allowing of adjustment of the lower button parts to the pitch of the upper button parts. According to 105 the invention this is effected by the pressing matrices 2 being made adjustable in the longitudinal direction, and in the case of multiple row arrangements also in the transverse direction, of the slide, and in such a 110 manner that when the slide is moved, they are positively adjusted to the pitch of the pressing dies 7 in the longitudinal and transverse directions.

In the example shown, the pressing matrices 115 2 are arranged in plates 14. The one matrix 2^a may for instance be fixed, while the other matrices are mounted in the plates 14 and are movable therein in the longitudinal direction (Figs. 1 and 5). The plates 120 14 carrying the pressing matrices 2 are mounted on the slide 1 and are movable in the transverse direction (Fig. 5).

The adjustment of the matrices 2 to the 125 pitch of the pressing dies 7 in the longitudinal direction is effected by means of fixed projections 12 (Figs. 1 and 5) during the forward pushing of the slide against which projections the press matrices which are arranged behind each other are caused to 130

strike successively, being thereby adjusted in determined distances from one another. When the slide is pushed back, the press matrices 2 are again pushed together in the 5 longitudinal direction to the pitch of the cutting dies for the lower button parts by means of projections 36 (Fig. 1).

The adjustment in the transverse direction of the slide, in the case of a two row arrangement of the press matrices, may be effected by means of a fixed key 13, and in the case of a multiple row arrangement by means of several such fixed keys 13 which may be secured with a cross piece 13^a (Fig. 15) to the slide guide 76. When the slide moves, the keys 13 engage between the plates 14 that carry the pressing matrices 2, whereby the pressing matrices are forced apart in rows. When the slide returns, the 20 plates 14 are pushed together again by means of guides 37, which for this purpose converge one toward the other (see Fig. 5).

The method of working of the machine is as follows:—

25 In the sheet metal strip 4 (Fig. 2) the lower button parts *a* are preliminarily pressed by means of a punch, then completely dished, and, if necessary, pierced. The dished, and if necessary pierced, lower 30 button parts are, in consequence of moving the sheet strip 4 (for instance by means of rollers 38, Fig. 2), adjusted over the pins 3^a of the bolts 3 and below the cutting dies 5. By means of the cutting dies 5 and the cutting 35 matrices 5^a the lower button parts are cut from the plate strips 4 and threaded on to the pins 3^a of the raised bolts 3 by any suitable means, for example with aid of rams or plungers 41 (Fig. 1), suitably acted 40 upon or, if the lower button parts were not previously pierced, they are pierced by the pins 3^a of the bolts 3 and simultaneously threaded on.

The cutting dies 5 are then raised and the 45 bolts 3 with the threaded-on lower button parts are lowered into the pressing matrices 2 (Figs. 1 and 5). In order to insure that the bolts 3 shall move down together with their driving member 41, the bolts are provided at their lower ends for instance with heads, which are guided in a T-shaped rail 40 (Figs. 1 and 6), thus insuring that all the bolts are pulled downward when the 50 member 41 is lowered.

55 At the same time, the upper button parts are cut from a second sheet strip introduced at 35^a by means of hollow cutting dies 8 co-acting with cutting matrices 10. By the following upward movement of the drawing dies 9, the cut out upper button parts are driven through the matrices 10 which thereby act as drawing dies and whereby the edges of the upper button parts are bent over. By a further upward movement of 60 the drawing dies 9, the bent-over upper but-

ton parts are pressed against piercing pins 11^a provided on dies 11, (Fig. 1). Through the coöperation of the pins 11^a of the dies 11 with corresponding holes in the drawing dies 9, the upper button parts are then pierced. The dies 11 are inserted into pressing dies 7 mounted in a slide 6. By a powerful pressure of the contoured drawing dies 9 on the contoured press dies 7, the upper button parts can be contoured. The completed upper button parts remain threaded on the pins 11^a of the dies 11 after the return of the drawing dies 9.

70 As soon as the drawing dies 9, as well as the bolts 3 have returned, so that the slide 1 and slide 6 no longer engage with the cutting block and the drawing dies, the two slides are moved toward each other and adjusted one above the other. During the movement of the slide 1, the plates 14 are 75 driven apart from each other through the action of the key 13, in such a manner, that at the end of the stroke of the slide the pitch *d* of the pressing matrices 2 (Fig. 5) is equal to the pitch of the pressing dies 7. 80 By the action of the projections 12, the pressing matrices 2 which are movable longitudinally in the plates 14 are adjusted at such a distance from each other longitudinally, that the pitch *f* of the pressing matrices 2 (Fig. 5) is equal to the pitch of the pressing dies 7. 85 At the end of the stroke of the two slides the lower button parts are accordingly located exactly under the upper button parts. 90

95 The plate 16, in which the pressing dies 7 are secured by means of nuts 17 (Figs. 7 and 8), is guided with projecting ends in grooves 43 of the ram 15, when the slide is moved to the left (Fig. 7). By the downward movement of the ram 15 the pressing dies 7 and also the piercing dies 11 (which are fixed in the plate 18 and secured by a plate 19 secured to plate 18 by screws) are moved downward. The plate 18 is arrested in its downward movement (for instance by 100 means of bushes 44 on the screws 75 (Fig. 1) before the pins of the piercing dies 11 come in contact with the pins of the bolts 3, so that on the further downward movement of the pressing dies 7, the upper button parts 105 are removed from the piercing dies 11 and threaded on to the pins of the bolts 3, on which are the lower button parts, and afterward their edges are bent over the lower button parts. The ram 15 now returns to 110 together with the pressing dies 7 and piercing dies 11.

115 In order to prevent the plates 18 and 19 from returning too far, stops are provided, for instance screws 75 Figs. 1 and 7. The 120 plate 16 and pressing die 7 are prevented from returning too far by the shoulders of the bushes 44 in the example shown.

125 The completed buttons which hang on the pins of the bolts 3 are raised from the press. 130

ing matrices 2 (Fig. 6) by raising the bolts 3.

For taking off and removing the complete buttons, a removing device 20 (Figs. 10 and 11) is provided in the space under the ram 15, which, in the example shown, is pivotally mounted in a movable fork 21 (Fig. 2). The fork 21, which is movably guided in the casting, is connected by means of a connecting member 22 to a lever 23. This lever 23 is rotatable about the bolt 24 and carries a roller 25, which works for instance in a cam-groove 26, whereby the removing device is moved backward and forward positively. The removing device 20 is moved under the raised buttons (Fig. 10) whereby upon the downward movement of the pins 3^a, the buttons are removed from the same through the action of the removing device and then lie on the latter. The removing device is now pulled back and thereby a lever 27 is knocked against a nose 28, whereby the removing device is swung upward, and the buttons are conveyed away along the sloping surface formed by the removing device. The slides 1 and 6 are now again pulled back into their original positions and the described working cycle is repeated.

In order to prevent the plate 16 with the pressing dies 7 from moving downward in the commencing position of the slide 6, two rails 45 (see Fig. 1) are provided in the slide casing 80 upon which rails 45 the plate 16 lies with its projecting end.

In Fig. 9 a modification of the machine is shown for the manufacture of buttons composed of upper, middle and lower parts. To the left is provided a device for dishing and piercing the lower button parts which device is constructed and arranged in the same manner as before described with regard to Fig. 1. The slide 1' moves, if shifted to the right, first below a second cutting block 48, which cuts out the middle button parts in exactly the same way, as this is done with the lower parts in the modification shown in Fig. 1. The middle parts are taken up by the piercing pins 3^{a'} of the bolts 3', above the lower button parts, as may be seen in Fig. 9. Thereupon the bolts 3' are lowered together with the lower and middle button parts reposing upon their piercing pins 3^{a'}, until these button parts are brought to rest in the pressing matrices 2'.

The device for the manufacture of the upper button parts is disposed on the right side of the drawing and is constructed in the same manner as in Fig. 1. Instead of the pins of the piercing dies there is a drawing die 49 rigidly connected with the die 11' and passing through a hole in the pressing die 7' as shown in the drawing and piercing a hole into this button part. Both slides 1' and 6' are moved to lay the one above the

other, in the same manner as described with regard to the modification shown in Fig. 1. Thereupon the upper button parts are shifted upon the middle and lower parts by lowering the pressing dies 7' and the drawing dies 49; by a continued downward movement of the pressing dies the outer edge of the upper button part is bent over the lower button part, whereupon the buttons are finished and are removed in the manner before described, by the removing device.

The slide 1' together with the pressing matrices 2' is shifted thereupon to the left into its starting position while the slide 6' is moved to the right also into its starting position.

Having now described my invention what I claim as new and desire to secure by Letters Patent is:—

1. In a machine for making buttons and the like articles each consisting of an upper part and a lower part, from sheet metal, the combination of a first slide, a plurality of lower pressing matrices for the lower parts, mounted in said first slide, a second slide, a plurality of upper pressing dies for the upper parts, mounted in said second slide, a plurality of cutting dies for cutting out the lower parts, a plurality of cutting dies for cutting out the upper parts, means for moving said first and second slides away from each other under said cutting dies, and means for moving said first and second slides toward each other, whereby they are moved out of the range of said cutting dies, and so as to bring said upper pressing dies immediately over said lower pressing matrices for pressing the upper and lower parts together to form complete articles.

2. In a machine for making buttons and the like articles, each consisting of an upper part, a middle part and a lower part, from sheet metal, the combination of a first slide, a plurality of lower pressing matrices for the lower parts, mounted in said first slide, a second slide, a plurality of upper pressing dies for the upper parts mounted in said second slide, a plurality of lower cutting dies for cutting out the upper parts, a plurality of upper cutting dies for cutting out the lower parts, a plurality of middle pressing matrices for pressing the middle parts, means for moving said first slide with the cut out lower parts under said middle, means to place the middle parts on the lower parts, means for moving said first slide with the lower and middle parts under the upper parts and means whereby the upper, middle and lower parts are pressed together to form complete articles.

3. In a machine for making buttons and the like articles, each consisting of an upper part, and a lower part, from sheet metal, the combination of a first slide, a plurality of lower pressing matrices for the lower

parts, mounted in said first slide, a second slide, a plurality of pressing dies in the said second slide, means for moving said first and second slides to and away from each other, and positive means for adjusting the pitch of said lower pressing matrices in conformity with the pitch of said upper pressing dies.

4. In a machine for making buttons and

10 the like articles, each consisting of an upper part, a middle part, and a lower part, from sheet metal, the combination of a first slide, a plurality of lower pressing matrices for taking up the lower parts, mounted in said first slide, a plurality of middle pressing matrices for the middle parts, a second slide, a plurality of upper pressing dies, means for moving said first and second slides to and away from each other, and positive means for adjusting the pitch of said lower and middle pressing matrices in their respective slides in conformity with the pitch of said upper pressing dies.

5. In a machine for making buttons and

25 the like articles, each consisting of an upper part, and a lower part from sheet metal, the combination of a first slide, a row of lower pressing matrices mounted in said slide, a second slide, a row of upper pressing dies mounted in said second slide, and means for adjusting the pitch of said lower pressing matrices, whereby the said pitch will be increased to the size of the pitch of said upper pressing dies by the movement of said first slide.

6. In a machine for making buttons and

30 the like articles, each consisting of an upper part, a middle part, and a lower part, from sheet metal, the combination of a first slide, a row of lower pressing matrices mounted in said slide, a row of middle pressing matrices for the middle parts, a second slide, a row of upper pressing dies mounted in said second slide, means for adjusting the pitch of said lower and middle pressing matrices, whereby the said pitches will be increased to the pitch of said upper pressing dies by the movement of said first slide.

7. In a machine for making buttons and

35 the like articles, each consisting of an upper part, and a lower part, from sheet metal, the combination of a first slide, a plurality of lower pressing matrices, arranged in two or more rows for the lower parts mounted in said first slide, a second slide, a plurality of upper pressing dies arranged in two or more rows mounted in said second slide, and means for adjusting said lower pressing matrices, longitudinally and transversely of said first slide, whereby said lower pressing matrices are caused by the movement of said first slide to coincide as to pitch both longitudinally and transversely with said upper pressing dies.

40 8. In a machine for making buttons and

the like articles, each consisting of a number of parts cut from sheet metal and connected together by pressing, the combination of a plurality of lower pressing matrices arranged in rows, a plurality of plates equal to the number of said rows, each row being mounted in a separate plate, and a slide on which all said plates are mounted so as to be capable of adjustment transversely of said slide.

45 9. In a machine for making buttons and the like articles, each consisting of a number of parts cut from sheet metal and connected together by pressing, the combination of a plurality of lower pressing matrices arranged in rows, a plurality of plates equal to the number of said rows, each row being mounted in a separate plate, and a slide on which all said plates are mounted so as to be capable of adjustment transversely of said slide, and means for effecting said transverse adjustment consisting of one or more fixed wedges adapted to move apart through the medium of said plates, the rows of said lower pressing matrices in the movement of said slide.

50 10. In a machine for making buttons and the like articles each consisting of a number of parts cut from sheet metal and connected together by pressing, the combination of a plurality of lower pressing matrices arranged in rows, a plurality of plates equal to the number of said rows, each row being mounted in a separate plate, and a slide on which all said plates are mounted, means for effecting longitudinal adjustment of the matrices consisting of stops against which said matrices located behind one another are caused to strike successively by the movement of said slide, and are thus adjusted at determined distances apart.

55 11. In a machine for making buttons and the like articles each consisting of an upper part and a lower part, from sheet metal, the combination of a first slide, a plurality of lower pressing matrices mounted in said first slide, a second slide, a plurality of upper pressing dies mounted in said second slide, a plurality of cutting dies for cutting out the lower parts, a plurality of cutting dies for cutting out the upper parts, means for moving said first and second slides away from each other under said cutting dies, and means for moving said first and second slides toward each other, whereby they are moved out of the range of said cutting dies, and so as to bring said upper pressing dies immediately over said lower pressing dies for pressing the upper and lower parts together to form complete articles, and a removing device for removing the complete articles, located between said first and second slides out of the range thereof, for removing with the upper surface the complete articles from the dies, and means for turning said removing device into an in-

clined position, whereby the complete articles are removed from the range of the machine.

12. In a machine for making buttons and the like articles each consisting of a number of parts cut from sheet metal and connected together by pressing, a plurality of lower pressing matrices mounted in a slide and means for effecting longitudinal adjustment of said matrices, consisting of steps against which the matrices located behind one another are caused to strike successively by the movement of said slide and are thus adjusted at determined distances apart.

13. A machine for making a plurality of buttons, each composed of a plurality of larger and smaller parts, comprising means

for cutting out the individual button parts from sheet metal, the cutting means being adapted to cut out the smaller button parts closer to each other than the larger button parts, means for adjusting the smaller button parts to the pitch of the larger button parts, and means to unite the said parts into buttons.

In witness whereof I have hereunto signed 25
my name in the presence of two subscribing
witnesses.
